UNITED STATES PATENT OFFICE.

CHARLES L. CURTIS, OF NEW YORK, N. Y., ASSIGNOR, BY MESNE ASSIGNMENTS, TO THE NORDLINGER-CHARLTON FIREWORKS COMPANY, OF SAME PLACE.

DESIGN FOR A FIRE-CRACKER BODY.

SPECIFICATION forming part of Design No. 30,658, dated May 2, 1899.

Application filed January 27, 1898. Serial No. 668,787. Term of patent 14 years.

To all whom it may concern:

Be it known that I, CHARLES L. CURTIS, a citizen of the United States, residing at New York, (Brooklyn,) county of Kings, and State of New York, have invented and produced a new and original Design for Fire-Cracker Bodies or the Like, of which the following is a specification.

My design consists of a fire-cracker body comprising, essentially, a hollow cylindrical body having open ends and contracted portions near each end, such contractions being sufficient to bring the inner surfaces of the wall of said body substantially into contact, closing the opening therethrough, and the exterior of the body having a spiral effect, due to the winding of the covering-strip, as shown in the accompanying drawings.

In the accompanying drawings, Figure 1 is

an elevation of the body, partially illustrating my design; and Fig. 2 is a central longitudinal section showing the contractions near the ends of said body.

1 indicates the whole cylindrical body.
2 indicates the spirally-wound cover-strip.
3 indicates the meeting edges of the said strip, and 4 4 indicate the contractions of the walls of the body.

What I claim is—

The design for a fire-cracker body substantially as shown and described.

Signed at the city, county, and State of New York this 25th day of January, 1898.

CHARLES L. CURTIS.
